UNITED STATES PATENT OFFICE.

ASA BRUCE BEALL, OF SEWICKLEY, PENNSYLVANIA.

DESIGN FOR A NUT-LOCK WASHER.

SPECIFICATION forming part of Design No. 33,022, dated July 31, 1900.

Application filed June 14, 1900. Serial No. 20,368. Term of patent 14 years.

To all whom it may concern:

Be it known that I, ASA BRUCE BEALL, a citizen of the United States, residing at Sewickley, in the county of Allegheny and State 5 of Pennsylvania, have invented and produced a certain new and original Design for a Nut-Lock Washer; and I do declare the following to be a full, clear, and exact description of the invention, such as will enable others skilled in the art to which it appertains to make and use the same.

The invention relates to a new and original design for a nut-lock washer; and it consists of a design of the shape and configuration 5 shown in the accompanying drawings, in which—

Figure 1 is a side elevation of my nut-lock washer. Fig. 2 is an end view. Fig. 3 is a top plan view, and Fig. 4 is a vertical sectional view taken on line $x-x$ of Fig. 3.

The leading feature of the design consists of a plate comprising two parallel sections a b , having coincident apertures c , a lateral extension d , and an inwardly-projecting extension e . The laterally-projecting extension 25 of the plate is provided with a triangular opening f , and the forward edge of the laterally-projecting extension is rectangular in form, as shown at g .

What I claim is—

The design for a nut-lock washer as herein shown and described.

In testimony whereof I have hereunto set my hand in presence of two subscribing witnesses.

ASA BRUCE BEALL.

Witnesses:

A. S. BEALL,
C. D. BEVINGTON.
